(57) **CLAIM**

The ornamental design for an electronic computer with display unit, as shown and described.

DESCRIPTION

FIG. 1 is a front view of an electronic computer with display unit, showing the new design.

FIG. 2 is a rear view of the electronic computer with display unit.

FIG. 3 is a right side view of the electronic computer with display unit.

FIG. 4 is a left side view of the electronic computer with display unit.

FIG. 5 is a top view of the electronic computer with display unit.

FIG. 6 is a bottom view of the electronic computer with display unit.

FIG. 7 is a front perspective view of the electronic computer with display unit, wherein the display screen is shaded to show translucency.

FIG. 8 is a rear perspective view of the electronic computer with display unit.

FIG. 9 is a front perspective view of the electronic computer with display unit, with the display unit shown in a tilted configuration; and,

FIG. 10 is a front perspective view of the electronic computer with display unit, with the display unit shown in another tilted configuration.

The present article is an electronic computer with a display unit that may be used for, for example, a POS (point of sales) system or other various applications. As illustrated in FIG. 7 and FIG. 8, the present article comprises: a display unit having a display screen, a heat releasing port provided as appropriate, and a base. As illustrated in FIG. 9 and FIG. 10, the angle of the display unit may be changeable.
